UNITED STATES PATENT OFFICE.

JACQUES KREISLER, OF NEW YORK, N. Y.

DESIGN FOR A PRONGED SETTING FOR A JEWEL-MOUNTING.

58,601.

Specification for Design.

Patented Aug. 2, 1921.

Application filed July 15, 1920. Serial No. 396,616. Term of patent 7 years.

To all whom it may concern:

Be it known that I, JACQUES KREISLER, a subject of Hungary, residing at New York, in the county of New York and State of New York, have invented a new, original, and ornamental Design for Pronged Settings for Jewel-Mountings, of which the following is a specification, reference being had to the accompanying drawing, forming part thereof.

The figure is a side elevation of a pronged setting for a jewel mounting applied to a ring, as shown.

I claim:

The ornamental design for a pronged setting for a jewel mounting, as shown.

JACQUES KREISLER.
